SUTURE PACKAGE

Cyrus F. Horine, Baltimore, Md.

Application April 4, 1939, Serial No. 266,009

6 Claims. (Cl. 206—63.3)

My invention relates to sterilized sutures, or ligatures used for suturing and tying in surgical operations and more particularly to a novel and improved form of suture bobbin for supporting and packaging a required length of suture strand in helically coiled form.

Prior to the invention herein disclosed, it was the practice to package and preserve a length of ligature or suture strand, known to the trade as catgut, by winding same into a concentrated coil, or upon a relatively stiff card-like reel, or preferably upon a rigid conical bobbin such as shown and claimed in my co-pending application, Serial No. 198,177, filed March 26, 1938. The coiled suture is thereafter treated and sterilized and finally maintained in a moistened, sterile condition by submerging same in a quantity of alcohol, or other suitable liquid, in a sealed transparent container, which may be broken on a predetermined line, to release the ligature for use.

Such prior products have the disadvantage that the strand is often damaged during the process of coiling and/or during sterilizing and packaging, so that the normal and desired twist in the strand is caused to open up at points when moistened, or to be otherwise weakened through contraction and expansion so that failure of the suture in use occurs. As is fully pointed out in my former application, above identified, this failure is due mainly to irregular and thus too rapid disintegration of strand portions of the ligature in contact with the tissue fluids.

As in the structure of my said prior application, it is likewise an object of the instant invention to overcome the tendency of the strand to become untwisted during packaging, and further to prevent such undue stretching of the strand as has caused weakening and untwisting thereof during contraction and expansion on dehydration and sterilization.

The improved bobbin, hereinafter described, overcomes these difficulties and has the advantage that the ligature is more easily and quickly withdrawn from the bobbin for use, and without kinking or the formation of knots when drawn taut.

By this invention the twist of the catgut strand, which is generally applied clockwise in its original preparation, is perfectly maintained and even increased by the operation of spirally winding the strand in a clockwise direction upon my contractable, conical bobbin. It will be understood, that in the practice of this invention, the ligature or suture strand may be originally twisted in either a right or left hand direction,

but that the strand must be wound upon the bobbin to correspond to the original twist in whichever direction it was performed, the direction of winding being always the same as the direction of the twist.

The instant invention has the further advantage that the ligature may be more uniformly wound in the form of a smoothly curved spiral upon the improved supporting cone which also serves to firmly retain the same in all contracted or expanded conditions thereof. Further, that due to the contractable structure of the bobbin the coil strand may be let off of the bobbin with greater ease and without chance of unwinding so that it may be drawn taut and thus straightened. By this structure and method of handling the coiled suture strand the original twist may be increased when the strand is thus straightened, so as to eliminate the formation of flattened or untwisted portions therein which may further result in the cutting of the flesh in use.

So that the invention of this application may be more readily understood it will now be explained that it is the common practice to wind a ligature or suture strand into the form of a concentrated loop or upon a reel or bobbin and to then place the same into a glass tube, one end of which is sealed. The ligature or suture package thus formed is then ready for sterilizing treatment prior to sealing the same. This treatment is usually accomplished by next placing into the open end of the glass tube a plug of cotton and the tube thus closed by the cotton is then placed in a vacuum dryer or machine to withdraw all water from the suture material and package within the tube. After drying, the tube and its contents are next sterilized at a temperature of approximately 300 degrees F., for at least one hour and these drying and sterilization steps of the treating process, generally cause a contraction of the strand in the longitudinal dimension; for instance, a sixty inch strand will contract from 2½ to 3 inches. A sterile hollow needle is next passed through the cotton plug, and through this needle a preserving solution is added to the glass tube containing the dehydrated and sterilized suture package. The tube is then ready for sealing off in the usual manner by means of a double or triple needle point gas flame. This sealing or closing of the tube takes place between the preserving solution level and the cotton plug, thus producing a hermetically sealed package approximately 4 inches in length.

The preserving solution, usually 95% alcohol, also serves as a vehicle to add a small amount of

moisture to the dehydrated suture or gut to make the gut pliable for use and at this point it has been observed that even this tiny amount of water in the preserving solution causes a marked 5 swelling of the strand which takes in its transverse diameter.

As a result of the longitudinal contraction or shrinkage of the strand during sterilizing treatment of the suture package and the subsequent 10 softening and swelling of the gut strand in the preserving solution it will have a tendency to finally untwist in the counterclockwise direction, the strand having been originally wound in a clockwise direction. This loss of twist or opening 15 up of the ribbon-like strand, in the solution, exposes more and more inner surfaces of the ligature material, in the package, and in use these exposed surfaces will be subject to the influence of tissue juices, which will actively engage said 20 surface portions and result in too rapid and unsatisfactory dissolution of the ligature. As a result, it has been observed that failure of the ligature through loss of twist therein, has followed 25 with very serious consequences as greatly affecting the success of operations.

A further object of my invention is to protect the sterile suture package during removal of same from the frangible container and during delivery and dispensing of the strand for use. It 30 is readily apparent that delivery of the strand from the container requires considerable exposure of the ligature to the hand, resulting in the chance of contamination of the sterile ligature with infectious bacteria, which in turn may 35 be transmitted to the wound. The protecting sheath and label carrying wrapper of this application is designed to overcome these disadvantages and to prevent cutting and damage to the coiled strand during breaking of the glass tube, 40 in which it is hermetically sealed.

The accompanying drawing illustrates a complete suture package as well as details of the improved bobbin and manner of winding the suture strand thereon, the product illustrated being intended to show the invention in its preferred form 45 wherein:

Fig. 1 is an enlarged side elevation of my improved suture package illustrating the manner in which it is sealed and immersed in a liquid container, which container is broken away longitudinally to illustrate such package in detail;

Fig. 2 is a greatly enlarged view in side elevation showing the suture package as it will appear when the bobbin is first wound with a length of ligature and/or after sterilization and moistening of the wound bobbin to return the strand thereof to normal condition;

Fig. 3 is a view similar to Fig. 2 showing the contracted suture package after treatment to dehydrate and sterilize the same, and

Fig. 4 is a fragmentary view in section showing the completed suture package within a sealing tube and protected by a conical label bearing sheath.

Referring to the drawing in detail, I have shown in Fig. 1 a tubular container 5, of the type in general use for this purpose, the container being preferably formed from a length of glass tubing hermetically sealed at opposite ends to 60 provide a transparent, frangible enclosure for a sterile suture package, indicated generally at 6. Within this glass enclosure 5, is further contained a quantity of alcohol or other ligature preserving and sterilizing liquid 7, and as shown in Fig. 4, a label 8, preferably formed of paper and provid-

ing a conical wrapper for the suture package may also be included, all as will be more fully described and claimed hereinafter.

The suture package 6 comprises a bobbin 9 upon which a length of suture strand 10, also referred to as ligature and catgut, is wound. It will here be noted that the winding of the strand 10 upon the bobbin is performed in accordance with the teachings in my prior application S. N. 198,177, i. e. for a right hand twisted strand the 10 direction of helical winding will be in a right hand direction, the direction of winding being always the same as the direction of twist.

The bobbin of this application is conical in shape and may be of the same configuration and taper as that disclosed in said prior application. Preferably, the bobbin comprises a circular base portion 11 which tapers very gradually towards the peak 12 of the conical body for about one quarter of the length of the body, beyond which 20 point, the taper is more abrupt to the peak or apex of the cone to facilitate removal of the coiled strand 10 without unwinding.

Extending transversely through the bobbin body 9, adjacent the base end 11, is formed an aperture 13, of such size as to receive one or both ends of the suture strand 10, which strand is helically wound on the tapered surface of the body to provide the package 6.

As is more clearly shown in Figs. 2 and 3, the 30 bobbin 9 is longitudinally divided, as at 14, by slitting or sawing through the tapered body, from the apex 12 to the aperture 13 through the base end 11, so that the major portion of the tapered body 9 is transversely resilient and may be readily contracted at right angles to the slit 14 there-through. By this construction stretching and weakening of the suture strand 10 is prevented during the usual steps of packaging and sterilizing the strand prior to sealing the same within 40 the glass container 5.

By reference to the showing in Fig. 2 it will be noted that the two longitudinally tapered, resilient connected portions of the bobbin body 9, are spaced uniformly by the slit 14 throughout the 45 length of these portions, and, further, that the suture strand 10 is snugly coiled on this conical split body, from the transverse aperture 13, to a point adjacent the apex 12, so as to be firmly supported by said bobbin.

The view of Fig. 2 further represents the condition and appearance of the strand 10 and bobbin 9 prior to, as well as after the usual treatment employed to render this suture package 6, sterile, whereas the view of Fig. 3 represents the 55 contracted condition of the strand and consequent compressed condition of the slit 14 in the supporting bobbin 90, which occurs during the usual treatment of dehydrating the suture package, prior to immersing and sealing the same in a 60 preserving liquid.

In prior devices employed for packaging lengths of catgut, the strand has been caused to stretch during sterilization due to the non-conforming or rigid nature of the bobbin or reel, or to be distorted in a direction counter to the twist in the strand, with the result that on subsequent softening and swelling of the strand in a preserving liquid it will have a tendency to untwist and to expose the weak and stretched tissue portions 70 thereof.

It will thus be seen that in all conditions of the suture strand under treatment upon my improved bobbin 9, stretching and distortion of the strand 10 will be prevented so that upon the addition of 75

the preserving liquid and consequent expansion, of the strand, that said strand will return to a substantially normal supported condition, as shown in Figs. 1 and 2.

5 In the view illustrated by Fig. 4, I have shown the parts of their normal assembled condition with the protecting sheath or wrapper 8 enclosing the major portion of the length of suture strand 10 coiled upon the bobbin 9. This wrapper 8 is 10 preferably formed from a sheet of paper or other relatively tough and flexible material on one side of which may be printed the number and size of the ligature strand, maker's name etc. The sheet may then be rolled into the form of a cone and 15 slipped over the wound bobbin, after which the free end of the suture is wound once or twice around the wrapper 8 and then secured by passing same through the aperture 13. In this manner the package is made secure. In use the 20 outer covering 8 also serves to protect the coiled twisted strand 6 on the bobbin 9 from being lacerated or severed when breaking the enclosing tube 5 and removing the bobbin, as shown in Fig. 4. Further, when it is desired to let the strand 25 off directly from the bobbin for use in so called free hand ligatures for tying blood vessels etc., considerable exposure of the ligature to the hand results with chance of contamination of the sterile ligature, were it not for the protecting cover 8.

30 What I claim is:

1. A suture package comprising a bobbin of conical form, a suture strand helically coiled on said bobbin, and a conical suture protecting sheath enclosing the coils of suture strand on said 35 bobbin.

2. A suture package comprising a bobbin of conical form, a suture strand helically coiled on said bobbin, a conical suture protecting sheath enclosing the coils of suture strand on said bobbin, and an end portion of said suture strand be-

ing wound over said sheath and secured to said bobbin.

3. In a suture package, a bobbin having a twisted suture strand wound helically thereon in a single layer with each convolution about the 5 bobbin in closely adjacent relationship and with a uniform twist in the suture strand from end to end thereof and a continuous smooth surface throughout, said bobbin having a longitudinally divided conical strand supporting body, and said 10 body being radially yieldable under contraction and expansion of said strand to maintain substantially uniform tension throughout the strand coiled thereon, whereby twist in said strand will not be caused to open while supported on or during 15 removal from said bobbin.

4. The structure defined in claim 3 in which a conical suture protecting sheath encloses the coils of suture strand on said bobbin.

5. In a suture package a surgical suture and 20 supporting bobbin therefor, the bobbin comprising a longitudinally divided transversely contractable conical body having normally spaced longitudinal edge portions, said body being substantially circular in cross-section throughout its 25 tapered supporting surface, and the suture comprising a uniformly twisted strand wound helically in a single direction and in a single layer on said tapered surface with each convolution in closely adjacent relationship, whereby the suture 30 strand is yieldably supported in the form of a conical coil to prevent untwisting of the strand under conditions of contraction and expansion thereof.

6. The structure defined in claim 5 in which a 35 transversely contractable protecting sheath of conical form encloses the coils of suture strand on said bobbin.

CYRUS F. HORINE.
